US00D895291S

(12) **United States Design Patent** (10) Patent No.: **US D895,291 S**
(45) Date of Patent: ** *Sep. 8, 2020

(54) **MESH BASKET**

(71) Applicant: **Design Ideas, Ltd.**, Springfield, IL (US)

(72) Inventors: **Christopher Hardy**, Springfield, IL (US); **R. Neal Post**, Springfield, IL (US)

(73) Assignee: **Design Ideas, Ltd.**, Springfield, IL (US)

(*) Notice: This patent is subject to a terminal disclaimer.

(**) Term: **15 Years**

(21) Appl. No.: **29/727,771**

(22) Filed: **Mar. 13, 2020**

(57) **CLAIM**

The ornamental design for a mesh basket, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front perspective view of a first embodiment of a mesh basket showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines represent environmental subject matter that forms no part of the claimed design.
